OVERLOAD INDICATOR FOR DIRECTIONAL RECEIVERS

Christopher Sydney Cockerell, Danbury, England, assignor to Radio Corporation of America, a corporation of Delaware

Application July 5, 1939, Serial No. 282,846
In Great Britain July 29, 1938

2 Claims. (Cl. 177—311)

This invention relates to radio direction finding receivers and more particularly to such receivers of that at present common kind which are not fitted with automatic volume control, but are fitted with manually operable sensitivity control effective upon a carrier stage or stages of the receiver.

The invention is illustrated in and explained in connection with the accompanying drawing in which Fig. 1 is a graph illustrating a receiver overloading effect; Figs. 2 and 3 are schematic diagrams illustrating, respectively, the invention applied to an anode bend detector, and to a grid leak detector; Fig. 4 is a schematic diagram of the invention applied to a diode detector; and Fig. 5 is a circuit diagram of a portion of a superheterodyne receiver employing the invention. Similar reference numerals will be used to indicate similar elements of the several figures.

It is found when operating a receiver of the kind referred to that errors of 180° are sometimes obtained and in order that the present invention may be the better understood, the reason for these occasional but very serious errors will first be described. The characteristic curve connecting input carrier (abscissae) with audio frequency output (ordinates) of a receiver of the kind referred to may take any of a variety of different forms, depending upon the detail design in the receiver, but in general is (as shown in Figure 1) a curve of bumped form. The audio frequency output (ordinates) increases with increase in input carrier strength (abscissae) until a certain input strength (B) is reached after which, for further increases of input carrier strength, the output decreases. The fact that the curve "turns over" in this way is a source of danger and is responsible for the phenomenon of "reversed sense," i. e. for the occasional errors to which reference has been made. It will be appreciated that if the manually operable sensitivity control is so set that the input when receiving any particular station, increases beyond that corresponding to the "crown" of the characteristic curve, the sense readings obtained may well be 180° wrong.

The object of the present invention is to avoid this defect and this object is achieved, according to the invention, by providing the receiver with warning means operable automatically if the carrier strength at a predetermined point in the receiver increases beyond a predetermined strength.

One way of carrying out the invention is to utilize the change of anode current of an anode

bend or of a grid leak detector to actuate a warning signal. Where a diode or similar type of detector is used, a fraction of the D. C. component of the rectified current may be fed to the grid of a following valve and the resulting change in anode current of this valve employed to actuate a warning signal.

In the embodiments shown in Figures 2 and 3, There is shunted across a resistance R_1 in the anode circuit of an anode bend (Figure 2) or of a grid leak (Figure 3) detector valve V—this valve may be and preferably is the normally provided detector of the receiver—a neon or other glow discharge tube circuit. The discharge tube circuit includes a discharge tube S in series with a resistance R_3 . The series combination is shunted by a condenser C_1 and is in series with a further resistance R_2 across the detector valve anode resistance R_1 . In the case of an anode bend detector (Figure 2) as the signal strength on the grid increases the valve V takes more current, the potential difference across the anode resistance R_1 increases, and the condenser C_1 charges up. In the case of a leaky grid detector (Figure 3) as the signal strength on the grid increases, the valve V takes less current but the anode potential rises and again the condenser C_1 charges up. In either case when the charge in the condenser C_1 is sufficient to cause the glow discharge tube S to break down through the resistance R_3 , the discharge tube S flashes, discharging the condenser C_1 which accordingly recharges until it again reaches a potential sufficient to flash the discharge tube.

Accordingly, the discharge tube flashes, or "winks" automatically so long as the signal input strength remains high. The circuit parameters are so chosen that if the carrier strength on the grid of the detector increases beyond the safe predetermined maximum, the tube S starts to flash and continues to do so until the carrier level is reduced again to a safe value, e. g. by the operator resetting his manual sensitivity control.

It will be noted that, in addition to giving a visual flashing warning, an audible warning will be heard in the normally provided telephones or loudspeaker due to the sudden stopping and starting of the discharge tube. The audio output to the telephones or the like may be taken off through condenser C_2 where the valve V is the normally provided detector of the receiver.

In the modification shown in Figure 4, a diode or oxide type of rectifier X is used. This rectifier, which again is preferably the receiver detector, feeds via the usual smoothing network

SN into the usual load resistance R₄. The "live" end of this load resistance is directly connected—i. e., not through the usual blocking condenser—to the grid G of a valve V₁. The normally utilized audio output is taken from the anode A of the valve V₁, the anode circuit of which includes the usual anode resistance R₁. Directly connected to the anode of this valve is a resistance R₂ in series with a condenser C₁. The condenser C₁ is shunted by a series combination of resistance R₃ and neon or other discharge tube S. With this arrangement, since the "live" end of the rectifier load resistance R₄ is directly connected to the grid G, a D. C. component of the rectified output from the rectifier is applied to the said grid. Accordingly, the anode current of the valve, and therefore its anode potential, will be a function of the carrier strength. In this arrangement also the discharge tube-condenser-resistance "winking" circuit is arranged to wink when the carrier strength exceeds the predetermined safe maximum.

Where the receiver is to receive continuous waves, a signal from the normally provided local heterodyne may be fed into the detector, this signal being of such value that it will not, in the absence of a strong carrier, operate the warning circuit. Figure 5 shows a circuit which is, in main essentials, very like that of Figure 4. In Figure 5 there are two rectifiers X₁, X₂, the circuit being part of a superheterodyne receiver employing two local oscillators (not shown). Intermediate frequency output derived by mixing the received signals with the first local oscillations are applied at I. F. and oscillations from the second local oscillator are applied at 2 LO. The valve V₁ in Figure 5 is shown as a tetrode but, from the point of view of this invention, the main difference between Figures 4 and 5 lies in the changed position of resistance R₃ which is provided to prevent excessive initial current flow at the commencement of discharge of the condenser C₁.

As will be appreciated, if the values of C₁ and R₂ are not properly chosen, the tube S will not "wink" i. e. it will light and remain alight, still acting as a warning though not so effective a warning as when it winks.

The warning device itself may take any of a variety of different forms; e. g., instead of a neon or other discharge tube, an electrical or mechanical relay actuating a warning lamp or

buzzer may be used or a cathode ray tube, or other visual indicating electron discharge device may be used.

In practice an arrangement in accordance with this invention operates not only as a warning device but as a rough visual indicator, indicating within a comparatively small arc the position of the minimum signal direction. This fact is of advantage since it considerably speeds up the process of taking a bearing by giving a rapid rough indication, the exact position of the minimum signal position being thereafter ascertained by the usual telephones or loudspeakers as in the usual way.

I claim as my invention:

1. In an overload signal device for a radio receiver, a detector responsive to signals applied to said radio receiver to produce a changing output current with increased signal strength, an output impedance for said detector, a network connected with the detector output impedance responsive to an output current resulting from overloading signals applied to said detector including a capacitor and a resistor connected to said detector output impedance in series and having charge and discharge periods of a rate below the persistence of vision for potentials corresponding to said overloading signals, and a visual warning indicator connected to said network between said resistor and capacitor and arranged to indicate by intermittent visual signals the application of signals overloading said receiver.

2. In an overload signal device for a radio receiver, a detector responsive to signals applied to said radio receiver to produce a changing output current with increased signal strength, an output impedance for said detector, a network connected with the detector output impedance responsive to an output current resulting from overloading signals applied to said detector including a capacitor and a resistor connected to said detector output impedance in series and having charge and discharge periods of a rate below the persistence of vision for potentials corresponding to said overloading signals, and a gaseous discharge warning indicator connected to said network between said resistor and capacitor and arranged to indicate by intermittent visual signals the application of signals overloading said receiver.

CHRISTOPHER SYDNEY COCKERELL.
